UNITED STATES PATENT OFFICE.

JOSEPH MACNAUGHTON, OF EDINBURGH, SCOTLAND.

PAPER-MAKING APPARATUS FOR SEPARATING SAND, METAL, AND OTHER IMPURITIES FROM PULP.

No. 813,984.

Specification of Letters Patent.

Patented Feb. 27, 1906.

Application filed November 23, 1905. Serial No. 288,764.

To all whom it may concern:

Be it known that I, JOSEPH MACNAUGHTON, paper-mill manager, a subject of the King of Great Britain and Ireland, residing at 3 Wester Coates Terrace, Edinburgh, Scotland, have invented new and useful Improvements in Connection with Paper-Making Apparatus for Effecting the Separation of Sand, Metal, and other Impurities from the Pulp, of which the following is a specification.

My invention has for its object to provide means whereby the separation of sand, metal, and other impurities from paper-pulp on its way to the breast of the paper-making machine is effected in a more efficient manner than hitherto by apparatus which occupies but small space and which can be cleaned with great ease in a much shorter time and with the use of a much smaller quantity of water than is necessary for cleaning the "sand-traps" hitherto used.

The apparatus according to my invention consists of a conical casing or vessel arranged in connection with the paper-making machine so that the paper-pulp on its way to the breast of the paper-making machine passes through the said casing or vessel, preferably so that the pulp has a circular or whirling motion through and around the said casing or vessel. The lower end of the said casing or vessel opens into a box or receptacle for the deposit of sand, metal, and other comparatively heavy impurities from the pulp, lighter impurities which rise to the surface of the pulp in the said casing or vessel being removed, preferably by passing off through an overflow in the casing or vessel situated at the part thereof whereat the said lighter impurities tend to collect, the said overflow being preferably provided with means by which its height can be adjusted. The purified pulp passes from the said casing or vessel by means of a pipe or passage extending down into the interior of the said casing or vessel to such a distance from the lower and upper parts thereof, respectively, as will not allow either the heavier or the lighter impurities aforesaid to pass off with the pulp to the breast of the paper-making machine.

I will describe with reference to the accompanying drawings an apparatus constructed in accordance with my invention, premising that I do not limit myself to the precise details illustrated.

Figure 1 is an elevation, and Fig. 2 is a plan.

The conical vessel A is open at bottom and communicates with a box B, having an outlet provided with a valve b for the withdrawal of deposited matter. The inlet C for the pulp to be purified is arranged so that the said pulp passes tangentially into the casing or vessel A, whereby the pulp has a circular or whirling motion as it passes down through the said casing or vessel. The said casing or vessel A is shown with plain sides; but it may have grooves or corrugations extending down its sides.

D is the pipe for the outlet of the purified pulp from the casing or vessel A, the lower end of the said pipe D opening into the interior of the said casing or vessel at a point such that the pulp will be drawn off as free as possible from impurities, the upper end of the said pipe D communicating with the outlet d, from which the pulp passes to the strainers and thence into the passage leading to the breast of the paper-making machine.

If desired, the pulp after passing from the casing or vessel A can pass through an ordinary sand-trap before passing to the strainers and breast.

In any suitable part of the apparatus—such as the outlet-pipe D, for example—there may be magnets to separate any fine magnetic particles which may not separate from the pulp in the casing or vessel A; but I do claim as my invention the use of magnets for separating magnetic particles from pulp.

E is an opening through the upper part of the casing or vessel A, constituting an overflow, as aforesaid, for any impurities which may rise to the surface of the pulp in the said casing or vessel A. The height of this overflow can be regulated by the weir e, capable of being raised and lowered by the screw e². The pulp which passes off with such floating impurities through any suitable pipe or passage can be separated by any convenient means, such as an auxiliary strainer, and returned to the supply of pulp to be purified.

At intervals, as desired, the deposited matter can be removed from the box B by opening the valve b, and when changing or washing up the paper-making machine my apparatus can be very efficiently and quickly cleaned with a much smaller amount of water than is required for cleaning ordinary sand-traps and with a minimum loss of pulp.

If desired, more than one apparatus as described can be used in series.

Having now particularly described and ascertained the nature of my said invention and in what manner the same is to be performed, I claim as my invention—

- 5 1. In connection with paper-making apparatus, a casing, or vessel, such as A, situated so that the pulp passes through it on its way to the breast of the paper-making machine, the said casing, or vessel, being provided, at bottom, with a box, or receptacle, for heavy impurities, and having an outlet, communicating with the interior of the said casing, or vessel, for the escape of purified pulp; substantially as hereinbefore described.
- 10 2. In connection with a paper-making apparatus, a casing adapted to permit the pulp to pass through it on its way to the breast of the paper-making machine, a box at the bottom of said casing for heavy impurities, and an outlet from said casing, in combination with an outlet for lighter impurities.
- 15 3. In combination with a paper-making machine, a casing adapted to permit the pulp

to pass through on its way to the breast of the paper-making machine, an inlet passing 25 tangentially into said casing, a box at the bottom of said casing for heavy impurities, and a central outlet from said casing for the escape of purified pulp.

4. In connection with a paper-making machine, a casing adapted to permit the pulp to pass through it on its way to the breast of the paper-making machine, an inlet passing tangentially into said casing, a box at the bottom of said casing for heavy impurities, and 35 a central outlet from said casing for the escape of purified pulp, in combination with an adjustable outlet for lighter impurities at the side of said casing.

In testimony whereof I have signed this 40 specification in the presence of two subscribing witnesses.

JOSEPH MACNAUGHTON.
